P. L. WEIMER.

Coiling Metal Pipe.

No. 22,044.

Patented Nov. 9, 1858.

Inventor:
Peter L. Weimer.

UNITED STATES PATENT OFFICE.

PETER L. WEIMER, OF LEBANON, PENNSYLVANIA.

IMPROVED MACHINE FOR COILING METAL PIPE.

Specification forming part of Letters Patent No. 22,044, dated November 9, 1858.

To all whom it may concern:

Be it known that I, PETER L. WEIMER, of Lebanon, in the county of Lebanon and State of Pennsylvania, have invented a new and useful Machine for Coiling or Bending into Coils Metal Pipe either Hot or Cold; and I do hereby declare that the following is a full, clear, and exact description of the construction of the same, reference being had to the annexed drawings, making part of this specification, in which—

Figure 1 is a side view. Fig. 2 is an end view. Fig. 3 is a view of the movable groove and roller from behind or opposite side to Fig. 1. Fig. 4 is a top view of the movable groove, the letters of reference corresponding in all figures. Fig. 5 is an arrangement by which the roller is dispensed with, and may be considered a modification of the same machine for producing the same effect.

The nature of my invention consists in providing a movable groove or die for the purpose of bending either hot or cold metal pipe into coils, which obviates the grooved cone or cylinder and enables the coil to be removed from the cone or cylinder without hindrance, as said cylinder or cone is a plain surface and made solid.

In order to enable others skilled in the arts to make and use my invention, I will proceed to describe its construction and operation.

A A is a shaft supported in the bearings B B. On one end of this shaft is fixed the cross-levers C. The other end is bored out taper to receive the cone or cylinder D, on which the pipe is to be coiled, which cone or cylinder is secured by the key E.

F is a cone with a plain surface bored and fitted on the shaft A and secured by the key N. On the surface of F is placed a coil of square solid iron, which coil is secured by small screws.

G is a square shaft, also sliding in the bearings B. On one end of this shaft on a journal works the lever H. The end of lever H under cone D forms the groove for the under or side nearest the cone D. The opposite side of the groove is formed by the grooved roller I.

L is a weight movable on lever H. Fig. 4 shows a top view of H, M N being the lips, which project inward to form the movable groove or die.

K is an arm secured to the shaft G. Said arm projects inward and upward, its end embracing the square coil on the cone F.

O is a lug cast on the cone D, through which passes the key to fasten the end of the pipe.

The die or movable groove can be so modified as to dispense with the roller, using in its stead the die or groove shown at Fig. 5. It will be observed that in both cases the die or groove forms a circular opening at the bending point of the pipe, which opening guides the pipe along the cone or mandrel, and at the same time prevents the pipe from flattening and loosing its circular section.

The manner of operating the above-described machine is as follows: The pattern coil being secured on the cone F, the lip of the arm K embracing the first coil, the plain-turned cone D is then fastened into the end of the shaft. The end of the piece of pipe to be coiled is inserted into the die N and fastened to the lug O by the key. By rotating the shaft A, the coil on F causes the shaft G to move outward and lay onto the cone D, an exact counter of the coil on F, the weight L at the same time being at the end of the lever, thus keeping the die or groove close to D. When the coil is completed, the pin is removed from the end of G and the weight L removed, a stroke of a wooden mallet loosens the coil on D, when it and lever H is slipped from off the end. The end of the pipe is now drawn through the die or groove, releasing H, the handles C rotated backward until K comes to its position when first started. H is now replaced and the machine is ready for another coil.

The peculiar advantage arising from the arrangement as herein represented is that one-inch-caliber pipe can be coiled into so small a coil as not to measure more than two inches inside diameter of coil at small end—a thing utterly impossible to accomplish with a grooved mandrel.

To the mechanic it will be apparent that the above-described machine may be variously modified—viz., the shaft G may be stationary and shaft A have the lateral play to produce the coil. Shaft G may also be placed directly under shaft A and dispense with lever H, fastening the die or groove on the end of the shaft

G. In place of F may be substituted a screw of regular or irregular pitch, all of which would, however, only amount to mechanical equivalents.

I do not claim any movable or springing arrangement for the purpose of keeping the movable die or groove in contact with the coiling mandrel during the operation of coiling the pipe; but,

Having thus fully described the nature of my invention and its mode of operation, what I claim as my invention, and desire to secure by Letters Patent, is—

1. The coiling of hot or cold metal pipe on a plain cone or cylinder by means of a movable groove or die, as herein fully described and specified.

2. Feeding the movable groove or die forward so as to form the coil by means of a pattern coil or its equivalent, as herein described and specified.

PETER L. WEIMER.
